UNITED STATES PATENT OFFICE.

ISAAC MERRICK PEASE, OF CINCINNATI, OHIO.

ARCH SUPPORT.

Application filed July 8, 1924. Serial No. 724,823.

To all whom it may concern:

Be it known that I, ISAAC M. PEASE, a citizen of the United States, residing at Cincinnati, in the county of Hamilton and State 5 of Ohio, have invented a new and useful Arch Support, of which the following is a specification.

One object of this invention is to provide an arch support in which a loop-shaped band 10 is adapted to be adjusted circumferentially of the foot of the wearer, the foot support within the band being connected to the band for adjustment in the direction of the axis of the band and longitudinally of the foot 15 of the wearer.

Another object of the invention is to provide novel means whereby the fastener which connects the pad with the band may be housed at one end within the pad, so that the fastener will not come into contact 20 with the foot of the wearer.

A further object of the invention is to provide a covering for the pad so that the foot of the wearer will not come into contact with the pad when the pad is made of 25 rubber. Another object of the invention is to provide novel ventilating means in the pad.

It is within the province of the disclosure 30 to improve generally and to enhance the utility of devices of that type to which the invention appertains.

Although preferred forms have been shown, it will be understood that a mechanic, working within the scope of what 35 is claimed, may make changes and improvements without departing from the spirit of the invention.

In the accompanying drawings:—

40 Figure 1 shows in end elevation, a device constructed in accordance with the invention;

Figure 2 is a bottom plan wherein parts are broken away;

45 Figure 3 is a top plan view of the pad, a portion of the foot-encircling band being shown;

Figure 4 is a section taken about on the line 4—4 of Figure 2;

50 Figure 5 is a section taken about on the line 5—5 of Figure 2;

Figure 6 is a transverse section of the pad, the view illustrating a slight modification.

55 The numeral 1 designates a loop-shaped foot-receiving band, the ends of which are overlapped as at 2, and connected together.

A reinforcing strip 3 is secured to the overlapped ends 2 of the band 1 and is located therebeneath. The band 1 preferably but not necessarily is elastic. A plurality of 60 tubular eyelets 4 are mounted in the overlapped ends 2 of the band 1 and in the reinforcing strip 3, the eyelets being spaced apart in a direction parallel to the axis of the loop-shaped band 1. The ends of the 65 eyelets 4 are riveted as at 5 on the reinforcing strip 3 and on the inner overlapped end of the band. A flexible protecting member 6 extends transversely of the band 1, beneath the reinforcing strip 3. The 70 ends of the member 6 are connected as at 7 to the band 1, at its opposite edges, but between the edges of the band, the protecting member 6 is free.

The device comprises a pad 8, preferably but not necessarily made of soft rubber. The upper surface of the pad 8 is convexed, as shown at 9. The pad 8 is located within the band 1 and rests on the lower portion of the band, as shown in Figure 1. A fastener is provided for connecting the pad 8 to the band 1. The fastener may be of any desired form, and may be vulcanized into the pad or be mounted therein otherwise. Preferably, however, a slit 10 is 80 fashioned in the upper surface of the pad 8 and extends partway through the pad, there being a reduced opening 11 communicating at its upper end with the slit and extended downwardly through the lower surface of 90 the pad. The fastener may be T-shaped, including a head 12 and arms 14. The head 12 of the fastener is located in the slit 10, and the slit closing above the head of the fastener, as shown in Figure 5, thereby preventing the head of the fastener from coming into contact with the foot of the wearer. The arms 14 of the fastener extend through 95 the reduced opening 11 of the pad 8 and may be mounted in any of the eyelets 4, thereby providing for an adjustment of the pad or foot support in the direction of the axis of the band and longitudinally of the foot of the wearer, it being possible to adjust the band 1 circumferentially of the foot 105 of the wearer. The ends of the arms 14 of the fastener are turned in opposite directions to form holding fingers 15, engaged with the lower end of the eyelet 4 through which the arms of the fastener pass. The 110 protecting member 6 prevents the fingers 15 of the fastener from coming into contact

110

with the shoe of the wearer, but because the member 6 is secured at its ends only to the band 1, the intermediate portion of the member 6 may be drawn aside, thereby giving access to the fingers 15 and permitting the fastener to be mounted in any of the eyelets 4. A porous covering 16, preferably made of cloth, is secured to the upper surface of the pad 8 and covers the slit 10. 10 The covering 16 exercises a two-fold office; first, it tends to keep the foot of the wearer from coming into contact with the pad 8, thereby preventing a heating or blistering of the foot, if the pad 8 happens to be made 15 of rubber; second, the covering 16 folds the pad 8 together and prevents it from opening at the slit 10. The pad 8 is provided with angular ventilating passages 17, opening through the pad at both ends and located in planes about parallel to the lower surface of the pad. For convenience, the passages 17 may be said to open at both ends through the side of the pad, at points between the top and the bottom of the pad. 20 25 When the pad 8 is compressed by the foot of the wearer, and permitted to expand, as the wearer walks, air will be expelled from and drawn into the passages 17, thereby ventilating the foot of the wearer. 30 In Figure 6, the pad is marked by the numeral 18 and one of the passages appears at 19. In this form, the covering, corresponding to the covering 16, and marked by the numeral 20 extends over the entire upper 35 surface of the pad and is carried beneath the pad at its edge, as shown at 21.

I claim:—

1. A device of the class described comprising a loop-shaped band and a resilient

foot support within the band, the support 40 having a ventilating passage located between the top and the bottom of the support and opening at both ends through the side wall of the support.

2. A device of the class described comprising a loop-shaped band and a resilient foot support within the band, the support having an angular ventilating passage located between the top and bottom of the support and opening at both ends through 50 the side wall of the support. 45

3. A device of the class described comprising a loop-shaped band and a resilient foot support within the band, the support having angular ventilating passages located 55 between the top and the bottom of the support, the passages opening at one end through the side wall of the support longitudinally of the support, and opening at their opposite end through the side wall 60 of the support transversely of the support. 60

4. A device of the class described comprising a loop-shaped band and a resilient foot support within the band, the support having a slit in its upper surface, and being provided with an opening leading downwardly from the slit through the lower surface of the support, a fastener comprising a head located in the slit, and an arm located 65 in the opening, the slit being closed above the head, and means on the band for engagement with the arm of the fastener, to hold the foot support on the band. 70

In testimony that I claim the foregoing as my own, I have hereto affixed my signature. 75

ISAAC MERRICK PEASE.
